REFILLABLE PENCIL

Stefan Steuer, Bohm.-Budweis, Czechoslovakia,
assignor to firm of Koh-i-noor Bleistiftfabrik
L. & C. Hardtmuth, Bohm.-Budweis, Czechoslovakia

Application November 13, 1935, Serial No. 49,587
In Czechoslovakia December 27, 1933

5 Claims. (Cl. 120—22)

This invention relates to refillable pencils in which the point section of the pencil is movable longitudinally in relation to the main portion or stem of the same, the lead passing with friction through the pencil point and being merely held in place by a clamping device but not propelled. According to the invention, in order that the length of lead exposed for writing purposes may always be kept constant, the clamping device is located in the immediate vicinity of the bore of the pencil point and the point section is drawn up, together with the said clamping device in such a way as to assist the clamping action of the latter.

15 Refillable pencils are already known which have a longitudinally movable point section and a clamping device, which serves only to hold the lead in place but in these known pencils the clamping device is arranged in such a way as to leave room for freely movable leads between such device and the bore of the pencil point, the latter carrying such leads with it when it moves downwards. In contradistinction hereto, in the pencil of the present invention, the clamping device is intentionally brought so close to the bore of the pencil point that there are no freely movable leads between it and the said pencil point, with the result that when the point descends the leads are not carried down with it.

20 On the contrary the point section, in its descent, moves away from the lead and only then is the latter released by the clamping means. Thus, each time the lead is released it can only drop far enough for its lower end to meet the bore 25 of the point; in other words, it always drops by a definite amount. If the point section and the clamping device then return to their positions of rest, the lead will project a definite distance beyond the bore of the point. This length 30 does not alter even though the pencil be operated a number of times and always readjusts itself anew when the lead is snapped off or worn down.

Furthermore, the movable point section and the clamping device are made of such shape that the point section assists the working of the clamping device. More specifically stated, the conical surface of the point-section when the latter is in its position of rest, bears upon the clamping device, which is made like a pin chuck and so presses the jaws of the chuck together.

Finally, the pencil according to this invention has the great advantage that upon unscrewing the movable point section, the clamping device 55 is exposed so that this clamping device and the

bore of the point section can easily be cleaned when fouled by lead dust, which might prevent them from functioning in a satisfactory manner.

One constructional embodiment of the invention is shown in the accompanying drawing, in which:

Fig. 1 shows the whole pencil in longitudinal section,

Fig. 2 is a section on the line II—II of Fig. 1,
Fig. 3 is a section on the line III—III of Fig. 1,
Fig. 4 is a detail in elevation and

Fig. 5 is a section on the line V—V of Fig. 4.

In the stem 1 of the pencil the part comprising the tube 2, designed to hold leads, and the clamping device 3 which embraces the lead 15 on all sides is arranged for longitudinal movement, while the clamping sleeve 4 is fixedly secured in the said stem. A spring 5 serves merely as a closing spring for the clamping device 3 and ensures retraction of the latter into the 20 clamping sleeve 4, thus causing the jaws of the clamping device to be pressed together so that a lead gripped therein cannot move longitudinally. The longitudinally movable tube 2 is surrounded by a wider and likewise longitudinally movable tube 6, provided at its lower end with two or more finger-like extensions 6^a (see Figs. 4 and 5) which pass through corresponding apertures or channels in the clamping ring 4 25 (see Figs. 1 and 2). The point section 8 is attached to these extensions 6^a, so that it is movable with the tube 6, and it has a bore 9, through which the lead passes with friction. A spring 7, independent of the clamp closing spring 5, normally holds the tube 6 and consequently the point 30 section 8 in their upper terminal position. On the upper end of the tube 6 is mounted a cap 10.

If the pencil be held by the stem 1 with the point 8 pointing vertically downwards, and if pressure be then applied to the cap 10, so that it moves downwards, against the pressure of the spring 7, the point section 8 (with its bore 9), being attached to the tube 6, will also be moved downwards while the tube 2 with the clamping 40 device 3 and the lead clamped therein at first remains at rest. Thus the point is forced off from the writing end of the lead. Only after a clearance *d* (Fig. 1) has been taken up in the descent of the cap 10 will the tube 2, with the clamping 45 device 3 also partake of the downward movement of the said cap, owing to the inner end 12 of the latter having now come into contact with the upper edge 11 of the tube 2.

Assuming the downward movement of the cap 55

10 to be continued, the clamping device 3 will now open, because it is pushed out of the clamping sleeve 4, and thus it frees a passage for the lead. A lead now feeds out of the tube 2 through the 5 clamping device 3 until it reaches the bore 9, which has also moved further down with the opening of the clamping device 3 and is, therefore, separated from the clamping device 3 by the normal distance plus the clearance d .

10 If the cap 10 be slowly released, both the clamping device 3 and the bore 9 move towards their positions of rest under the action of the springs 5 and 7. The lead which has fallen down as far as the bore 9 takes part in this rearward movement up to the moment at which the clamping device closes. From this moment the clamping device 3 and the firmly clamped lead remain stationary and only the point section 8 with its bore 9 continues its return movement under the action 15 of the spring 7. In doing this the bore 9 pushes itself over the stationary lead which, when the return movement of the member 8 is completed, projects from the bore 9 by the amount of the clearance d . The point section 8, upon completion 20 of its return movement, also comes into contact with the clamping device 3 and therefore, again assists the clamping action by pressing together 25 the clamping or chuck jaws.

By varying the clearance d the length of lead 30 projecting beyond the bore 9 after conclusion of the described lead adjusting movement can be varied.

On the repetition of the above described cycle of operations without any alteration of the length 35 of the protruding piece of lead pressure on the cap does not produce any change in the position of the lead, this being one feature which distinguishes the pencil of the present invention from known constructions. Only when the length of 40 lead which projects from the bore 9 has been reduced (for instance, by snapping it off or wearing it down by writing) does any advance of the lead take place in response to the described lead adjusting operation. Further when an advance of 45 the lead does take place it can only be such that, at the conclusion of the lead adjusting operation, the lead protrudes by the same amount d from the bore 9.

Variation of the clearance d may, for instance, 50 be effected by turning the cap 10 on the screw thread 13, which the tube 6 carries at its upper end. Accidental rotation of the cap 10 can be prevented by any convenient means as by a close

frictional engagement between the cap and the tube 6.

What I claim is:

1. A refillable pencil, comprising a stem, a point section longitudinally movable relatively to said stem and having a bore through which passes the lead with friction, a likewise movable lead clamping device, an adjusting device cooperating with said point section and with the clamping device so as to move, when operated, first, only the point section and thereafter also the clamping device in the same direction, means movable relatively to and cooperating with the clamping device so as to make it operative, and spring means to return the clamping device and the point section to their original position. 10

2. A refillable pencil, as claimed in claim 1, wherein the clamping device is arranged in the vicinity of the point section.

3. A refillable pencil, comprising a stem, a point section longitudinally movable relatively to said stem and having a bore through which passes the lead with friction, a likewise movable lead clamping device, a tube carrying said point section, a further tube concentrically arranged to the first named tube and carrying said clamping device, a cap-like adjusting member cooperating with both tubes so as to move, when operated, first only the first named tube and thereafter also the last named tube in the same direction, means secured 30 to said stem, cooperating with said clamping device to make it operative, and spring means to return both tubes to their original position. 35

4. A refillable pencil, comprising a stem, a point section longitudinally movable relatively to said stem and having a bore through which passes the lead with friction, a likewise movable lead clamping device arranged in the vicinity of said point section, an adjusting device cooperating with the point section and with the clamping device so as to move, when operated, first only the point section and thereafter also the clamping device, a sleeve-like member secured to said stem and embracing said clamping device to actuate the latter, when being displaced relatively to the same, 45 and spring means to return the clamping device and the point section in their original position.

5. A refillable pencil as claimed in claim 4, wherein the point section and the clamping device are provided with corresponding cam surfaces 50 cooperating when being displaced relatively to each other.

STEFAN STEUER.
